UNITED STATES PATENT OFFICE.

CHARLES W. HUEBARD, OF BOSTON, MASSACHUSETTS.

SPINNING AND TWISTING APPARATUS.

1,240,214.

Specification of Letters Patent. Patented Sept. 18, 1917.

Application filed May 3, 1915. Serial No. 25,385.

To all whom it may concern:

Be it known that I, CHARLES W. HUEBARD, a citizen of the United States, residing at Boston, county of Suffolk, State of Massachusetts, have invented an Improvement in Spinning and Twisting Apparatus, of which the following description, in connection with the accompanying drawing, is a specification, like characters on the drawing representing like parts.

This invention relates to spinning and twisting apparatus of that type adapted to wind yarn in a yarn mass in layers extending transversely to the axis of rotation, and the object of the invention is to provide a novel machine of this type in which all reciprocating parts are eliminated so that the only motion which any of the parts have is a rotary motion. By thus eliminating all reciprocating motions and using only parts which have a rotary motion a device is provided which will run at a very high speed without any jar or vibration and by which the yarn produced will be even and uniform in size.

In order to give an understanding of my invention I have illustrated in the drawings a selected embodiment thereof which will now be described, after which the novel features will be pointed out in the appended claims.

Referring now to the drawings, Figures 1 and 2 are vertical sectional views through a winding and twisting head embodying my invention, said views being taken at right angles to each other, Fig. 1 being taken on substantially the line $x-x$, Fig. 3, and Fig. 2 on the line $y-y$, Fig. 3;

Fig. 3 is a section on the line $a-a$, Fig. 1; Fig. 4 is a section on the line $b-b$, Fig. 2.

My apparatus is of that type involving a yarn receiver adapted to receive the yarn mass being wound, a winding plate which rests on one end of the yarn mass and has a rotary movement relative thereto and means for traversing the yarn radially as the winding plate rotates thereby to lay the yarn in layers extending transversely to the axis of rotation.

The yarn receiver may have any suitable or usual construction and is shown more or less diagrammatically at 1, said yarn receiver being mounted for rotation and adapted to receive a yarn mass 2. The

winding plate is shown at 3 and it rests on one end of the yarn mass and is provided with a radial slot 4 through which the yarn 5 is delivered. This winding plate 3 is rotatably mounted, as usual in machines of this type, but it rotates at a different speed than the yarn mass and yarn receiver so that a winding or yarn-laying action will take place due to the relative movement of the winding plate and yarn receiver.

In devices of this type as heretofore constructed an oscillatory yarn guide has been employed for traversing the yarn back and forth in the slot. By my invention I eliminate this oscillatory element and substitute therefor a rotary element.

The winding plate 3 is herein shown as sustained on a shaft 6 which is driven by a suitable gear 7, said shaft being hollow so that the yarn may pass down through it from a source of supply. The yarn guide 8 by which the yarn is traversed in the slot 4 is in the form of a rotary cam element 8 which rotates relative to the winding element. Associated with the yarn guiding or traversing member 8 is a compensating member 9 also in the form of a cam which is rigid with the member 8. The yarn 5 passes down through the hollow shaft 6, out through the opening 10, and around one edge of the member 9, thence to the opposite edge of the yarn-guiding member 8, and thence through the slot 4 to the yarn mass 2. A suitable guiding element 11 is associated with the compensating element 9 with which the yarn has engagement and which holds the yarn in proper position on the compensating element. The object of the compensating element is to compensate for the radial traverse of the yarn so that the yarn will be drawn through the shaft 6 with an approximately uniform speed regardless of whether it is being laid on the periphery or toward the center of the yarn mass 2. The periphery of the compensating element 9 is so designed relative to the element 8 that it acts on the yarn to place an increasing amount of slack therein as the yarn-laying element 8 lays the yarn in toward the center of the yarn mass or toward the inner end of the slot 5, said element 9 operating to give up the slack in the yarn as the point at which the yarn is being laid moves outwardly toward the outer end of

the slot 4. The yarn will thus be drawn through the tube 6 with an approximately uniform movement.

These two yarn-controlling elements 8 and 9 may be given their rotary motion in any desired way. I have herein shown a construction wherein their rotary motion is derived partly from the rotary motion of the shaft 6 and partly from the rotary motion 10 of a second shaft 12 through which the shaft 6 extends, said shaft 12 being driven by a suitable gear 13 at a different rate of speed from that of the shaft 6. The shaft 6 is shown as having rigid therewith a housing 15 or casing 14 in which is mounted a shaft 15 carrying at its upper end a gear 16 meshing with a gear 17 fast on the shaft 12. The shaft 15 carries at its lower end a pinion 18 which meshes with a gear 19 fast on a 20 sleeve 20 that rotates freely about the shaft 6 and to which the elements 8 and 9 are fixedly secured. The gears 17 and 19 have a different number of teeth thereon, and since the housing 14 with the shaft 15 rotates 25 bodily with the shaft 6 the differential movement between the shafts 12 and 6 will operate through the gearing above described to give the yarn-controlling elements 8 and 9 a rotation at a different speed from that 30 of the winding plate 3. This housing 14 is preferably made oil-tight so that the gears may run in oil and as all of the parts of the device are rotary parts and no reciprocating parts are employed, the device may be 35 operated at a high speed without producing any undesirable jar or vibration. Moreover, as the compensating element 9 operates to compensate for the in-and-out traverse of the yarn, said yarn will be drawn through 40 the shaft 6 from the source of supply at an approximately even rate of speed, thus obviating any possibility of breakage of yarn due to an uneven feed.

I have shown at 21 an anti-friction bearing 45 between the gear 17 and the central or hub portion of the housing 14, the purpose of which being to reduce friction.

It will be understood, of course, that provision will be made so that as the thread 50 mass 2 is built up the winding plate with its associated mechanism will rise or the thread mass will be depressed. I have not shown in the drawings any provision for this as it forms no part of the present invention.

55 While I have illustrated herein a selected embodiment of the invention, I do not wish to be limited to the constructional features shown.

I claim:

60 1. In a winding and twisting apparatus, the combination with a yarn support, of a winding plate adapted to rest on the yarn mass sustained on said support and provided with a yarn-guiding slot, means to rotate 65 said yarn support and winding plate relative

to each other, and a disk-like yarn-guiding member having a peripheral edge over which the yarn passes as it is delivered to said slot, and means to rotate said yarn-guiding member relative to the winding-plate.

2. In a winding and twisting apparatus, the combination with a yarn support, of a winding plate adapted to rest on the yarn mass sustained on said support and provided with a yarn-guiding slot, means to rotate 70 said yarn support and winding plate relative to each other, a disk-like yarn-guiding member having a peripheral edge over which the yarn passes as it is delivered to said slot, means to rotate said yarn-guiding member relative to the winding plate, and means to maintain the yarn in engagement with said edge.

3. In a device of the class described, the combination with a yarn support, of a winding plate adapted to rest on the yarn mass and provided with a yarn-guiding slot, means to rotate the yarn support and winding plate relative to each other, a rotary 85 yarn-guiding member acting directly on the yarn, means to rotate said member relative to the winding plate whereby the yarn is given a radial traversing movement in the slot of the winding plate, and a compensating member rotating with the yarn guide 90 and operating to place slack in and let it out of the yarn as the latter traverses toward and from the center of the yarn mass.

4. In a device of the class described, the combination with a yarn support, of a winding plate adapted to rest on the yarn mass and having a radial yarn-guiding slot, means to rotate the yarn support and winding plate relative to each other, a rotary 100 yarn-guiding member having a peripheral 105 eccentrically-situated edge over which the yarn passes as it is delivered to said slot, and means to rotate said yarn-guiding member relative to the winding plate.

5. In a device of the class described, the combination with a yarn support, of a winding plate adapted to rest on the yarn mass sustained on said support and provided with a yarn-guiding slot, means to rotate the yarn support and winding plate relative to each other, a rotary 110 yarn-guiding member having a peripheral eccentric yarn-guiding edge over which the yarn passes to the yarn-guiding slot, means to rotate said yarn-guiding member relative to the winding plate 115 thereby to give the yarn a radial traverse in said slot, and means to place slack in and let it out of said yarn as the latter is traversed toward and from the center of the yarn mass.

6. In a device of the class described, the combination with a yarn support, of a winding plate adapted to rest on the yarn mass sustained on said support and provided with a yarn-guiding slot, means to rotate the 120 125

yarn support and winding plate relative to each other, a rotary yarn-guiding member having an eccentric yarn-guiding edge over which the yarn passes to the yarn-guiding slot, means to rotate said yarn-guiding member relative to the winding plate thereby to give the yarn a radial traverse in said slot, and a compensating member having an eccentric yarn-guiding edge and rotatable with the yarn-guiding member to place slack in and let it out of the yarn as the latter traverses toward and from the center of the yarn mass.

7. In a device of the class described, the combination with a yarn support, of a winding plate adapted to rest on the yarn mass and provided with a radial yarn-guiding slot, means to rotate the yarn support and winding plate relative to each other, means to traverse said yarn in said slot, a rotatable compensating member having an eccentric peripheral edge over which the yarn passes during its passage to said traversing means, and means to rotate said compensating member relative to said winding plate thereby to place slack in and take it out of the yarn as it traverses toward and from the center of the yarn mass.

8. In a device of the class described, the combination with a yarn support, of a winding plate adapted to rest on the yarn mass and provided with a yarn-guiding slot, means to rotate said yarn support and winding plate relative to each other, a rotary yarn-guiding member situated co-axially of the winding plate, and provided with a peripheral yarn-guiding edge over which the yarn passes as it is delivered to said slot, and means to rotate said yarn-guiding member and winding plate relative to each other.

9. In a device of the class described, the combination with a rotatable yarn support, of yarn-winding means operating to wind a

yarn mass on said support in layers extending transversely to the axis of rotation, said 45 yarn-winding means including a rotatable yarn-guiding member having an eccentric peripheral yarn-guiding edge over which the yarn passes as it is delivered to the yarn support.

10. In a device of the class described, the combination with a rotatable yarn support, of yarn-winding means operating to wind a 50 yarn mass on said support in layers extending transversely to the axis of rotation, said 55 yarn-winding means including a rotatable yarn-guiding member having an eccentric peripheral yarn-guiding edge over which the yarn passes as it is delivered to the yarn support, and a rotatable compensating member situated co-axially of the winding means and operating to place slack in the yarn and to take it out of the yarn as the latter traverses toward and from the center of the 60 yarn mass.

11. In a device of the class described, the combination with a rotatable yarn support, of a winding plate adapted to rest on the 65 yarn mass sustained on said support and provided with a radial yarn-guiding slot, 70 means to rotate said yarn support and winding plate relative to each other, a rotatable yarn-guiding member having an eccentric peripheral yarn-guiding edge over which the yarn passes as it is delivered to the yarn 75 support, a rotatable compensating member also having an eccentric peripheral yarn-guiding edge over which the yarn passes as it is delivered to the yarn-guiding member, and a yarn guide acting on the yarn and 80 maintaining it in engagement with the compensating member at a point opposite the yarn-guiding slot.

In testimony whereof, I have signed my name to this specification.

CHARLES W. HUBBARD.
